UNITED STATES PATENT OFFICE.

STEPHEN E. SPOFFORD, OF LYNN, MASSACHUSETTS.

SCREW DRIVER.

Application filed June 10, 1927. Serial No. 197,811.

The invention relates to screw drivers having a gripping tool for holding the screw on the screw driver ends so that the operator will not have to hold the screw in his 5 fingers while the screw is being started.

The invention consists of a gripping tool encompassed by a screw driver member which is constantly held outwardly beyond the ends of the screw driver by a coil spring. 10 The gripping tool is normally at right angles to the screw driver ends and is suitably anchored to a flat spring which allows the gripping tool to turn against the tension of the said flat spring, the opposite end 15 of which is anchored in a stationary support near the handle.

The gripping tool is first placed in the slot cut in the screw and then turned around against the tension of the flat spring to 20 about ninety degrees, or parallel with the screw driver ends. The screw, gripping tool and the flat spring are then forced inwardly until the screw driver ends enter the slot in the screw. When the gripping tool and 25 the screw driver ends are in position the gripping tool by the tension of the flat spring causes the sides to bind against the side of the slot in the screw, thereby holding the screw in position so that the operator 30 will not use his fingers to get the screw started.

The object of the invention is to provide a cheap and practical device for holding the screw on the screw driver so that the operator 35 will not have to hold the screw in his hand while it is being started.

Referring to the figures: Figure 1 is an elevation of a screw driver with a screw held in position.

40 Figure 2 is a longitudinal section of the screw driver showing the various parts with the gripping tool in the outward position.

Figure 3 is a longitudinal section taken ninety degrees from the section line in Figure 2, showing the gripping tool in position in the slot of the screw.

Figure 4 is a section showing the screw held by the gripping tool.

Figure 5 is a plan view of the screw showing the slot.

Figure 6 is a cross section taken across the screw driver ends and the gripping tool.

55 Figure 7 is a cross section taken across the screw driver ends and the gripping tool when set in the screw slot.

Figure 8 is a cross section of the tube and flat spring looking upwardly.

Figure 9 is a cross section of the tube and flat spring looking downwardly. 60

Referring to the drawings, similar numerals refer to similar parts throughout the several views. In the form which I have chosen to illustrate the principles of my invention, the numeral 10 of the screw driver 65 represents the shell of the tool which is provided at its working end with a bushing 11. This bushing is tapered at 12 and 13 and adapted to set into a slot 14 of the screw 15 for placing the screw in position 70 by turning the screw driver manually. Securely fastened to the opposite end of the screw driver is an operating handle 16. The center of the bushing 11 is bored out and is adapted to receive the gripping tool 17 75 which extends through the bushing 11 in the tube and operates or controls the gripping mechanism. The bushing 11 is rigidly secured to the shell 10 and is held in position by the pins 18 and 19. The pins 18 80 and 19 were originally one piece of metal and extended through the space occupied by the tool 17. After the pin is put solidly in position the portion extending through the bore is drilled out, making two pieces as 85 shown. The outer end of the gripping tool 17 is tapered, as indicated at 20 and adapted to set into the slot 14 of the screw 15. Integral with the opposite end of the gripping tool 17 is a head 21 provided with a deep slot 90 22. The slot 22 is adapted to receive the flat spring 23, the opposite end of which rests in the slot 24 formed in the elongated head 25. The head 25 is formed integral with the bushing 26 which is rigidly secured 95 to the shell 10 by the pin 27. The pin 27 extends into the shell 10 and holds the handle 28 rigidly in position. Encompassing the head 25 is a coil spring 29 whose ends rest against the bushing 26 and the flat 100 spring 23. The coil spring 29 constantly forces the flat spring 23 and the gripping tool 17 outwardly as shown in Figure 3.

In operation the screw 15 is placed on the gripping tool 17 as indicated in Figure 3. 105 The screw gripping tool 17 and head 21 is turned against the tension of the spring 23 as shown in Figure 4 and pressed downwardly until the screw driver ends, 12 and 13, enter the slot 14 of the screw 15 and is held in position by the sides of the gripping tool which allows the operator to start the 110

screw without holding it with his fingers. It will be seen that when the screw is pushed downwardly that the flat spring 23 is pushed against the coil spring 29 and is free to slide axially into the slot formed in the elongated head. This operation allows the screw to be held in position while the operator is placing it.

What I claim as new and desire to secure 10 by Letters Patent of the United States is—

1. A screw driver and a screw holding means comprising a screw driver bit, a rod having a holding bit end centrally located in a bore formed in the screw driver bit, 15 and means to yieldingly project the bit part of the said rod beyond the main body of the driver bit and a second means for yieldingly holding the projecting bit shaped part of the rod at right angles to the bit 20 shaped portion of the body whereby the slot of the screw may be engaged by the projecting bit portion of the rod and the said bit portion turned into alignment with the bit portion of the body and thrust back so that 25 the slot of a screw may be engaged with the bit portion of the body and there held by

the reaction of the driver bit and the bit portion of the rod in opposite direction on opposite walls of the screw slot.

2. A screw driver and screw holding 30 means comprising a shell, a handle in one end of the shell, a screw driver bit in the opposite end of the shell, a rod having a holding bit and centrally located in a bore 35 formed in the screw driver bit, a coil spring to yieldingly project the bit part of said rod beyond the main body of the driver bit, a flat spring inserted into slots formed in the handle and the holder rod for yieldingly holding the projecting bit shaped part of the rod at right angles to the bit shaped portion of the body whereby the slot in a screw may be engaged by the projecting bit portion of the rod and the said bit portion turned into alignment with the bit of the 40 body and thrust back so that the slot of the screw may be engaged with the bit portion of the body and there held by the reaction of the driver bit and the bit portion of the rod in opposite direction on opposite walls 45 of the screw slot.
